(57) **CLAIM**

The ornamental design for a beekeeper jacket as shown and described.

DESCRIPTION

FIG. 1 is a front view of a first embodiment of a beekeeper jacket showing my new design.

FIG. 2 is a rear view thereof.

FIG. 3 is a front view of a second embodiment of a beekeeper jacket showing my new design, the rear view being identical to FIG. 2.

FIG. 4 is a front view of a third embodiment of a beekeeper jacket showing my new design, the rear view being identical to FIG. 2.

FIG. 5 is a front view of a fourth embodiment of a beekeeper jacket showing my new design, the rear view being identical to FIG. 2.

FIG. 6 is a front view of the first embodiment of the beekeeper jacket showing my new design in another configuration of use.

FIG. 7 is a rear view of the first embodiment of the beekeeper jacket showing my new design in another configuration of use.

FIG. 8 is a front view of the first embodiment of the beekeeper jacket showing my new design in another configuration of use; and,

FIG. 9 is a rear view of the first embodiment of the beekeeper jacket showing my new design in another configuration of use.

The thinner dashed broken lines in the drawings depict portions of the beekeeper jacket which form no part of the claim. The thicker dashed broken lines depict stitching or other portions of the design which also form no part of the claim. The additional thinner dashed broken lines in FIGS. 6-9 depict different headgear configurations of use which form no part of the claimed design.

1 Claim, 9 Drawing Sheets
